Specification for Design.

Patented Jan. 16, 1917.

Application filed November 8, 1916. Serial No. 130,280. Term of patent 7 years.

To all whom it may concern:

Be it known that we, ROBERT G. WAGNER and ERNEST J. SCHWEITZER, citizens of the United States, residing at Los Angeles, in the county of Los Angeles and State of California, have invented a new, original, and ornamental Design for a Canopy, Hanger, and Pan for a Lighting-Fixture, of which the following is a specification, reference being had to the accompanying drawing, forming part thereof.

The figure is a side elevation of the canopy, hanger and pan.

We claim:

The ornamental design for a canopy, hanger, and pan for a lighting fixture as shown.

In witness that we claim the foregoing, we have hereunto subscribed our names this 11th day of October, 1916.

ROBERT G. WAGNER.
ERNEST J. SCHWEITZER.
